UNITED STATES PATENT OFFICE.

CHARLES V. WOERD, OF WALTHAM, MASSACHUSETTS.

STEM WINDING AND SETTING MECHANISM FOR WATCHES.

SPECIFICATION forming part of Letters Patent No. 340,850, dated April 27, 1886.

Application filed November 9, 1885. Serial No. 182,278. (No model.)

To all whom it may concern:

Be it known that I, CHARLES V. WOERD, of Waltham, in the county of Middlesex and State of Massachusetts, have invented certain new and useful Improvements in Stem-Winding Watches, of which the following is a full, clear, and exact description.

The stem winding and setting mechanism of this invention consists in substance of an arbor or spindle to which the stem or pendant of the watch-case is detachably connected, and which is capable of sliding in its bearings, and is provided with a pinion-wheel to engage with the setting mechanism of the watch and a loose gear-wheel to engage with the winding mechanism of the watch, and which is adapted to be clutched with a clutching-collar attached to the arbor, in combination with a spring adapted to bear upon the arbor, and all in such manner that the arbor in its normal position is in connection with the winding mechanism, and to place it into connection with the setting mechanism requires to be drawn outwardly. The spring in one of its bearings on the arbor holds it in its normal position—that is, with the arbor engaged with the winding mechanism—and in its other bearing upon the arbor it holds the arbor in connection with the setting mechanism until relieved by pushing the arbor inwardly.

In the accompanying plate of drawings the present invention is illustrated, and Figure 1 is a central vertical section through the pillar and top plates of a watch-movement and other parts thereof necessary to illustrate the connection of the mechanism of this invention therewith; and Fig. 2 is a plan view of the mechanism of this invention, and showing in dotted lines those portions of the train of gears making up the watch-movement, which make more particularly direct connection therewith.

In the drawings, A represents the pillar-plate; B, the top plate; C, the center-wheel; D, the hour-wheel; E, the cannon-pinion; F, the crown-wheel; G, an intermediate wheel connecting crown-wheel F with the winding-barrel, all as usual in watch-movements, and therefore needing no particular description herein.

H is an arbor or spindle located between the

pillar and top plate, A B, and extending in a parallel direction therewith, turning at its end portions in bearing-blocks J of the pillar-plate. This arbor or spindle is the winding and setting arbor of the watch-movement, and at its outer end it has the stem or pendant K of the watch-case screwed into the same, thus allowing said pendant to be detached at pleasure from the winding-arbor by unscrewing it therefrom, the arbor at such time being fastened against movement by turning up a set-screw, L, against it. This set-screw passes loosely through the top plate and screws into one of the bearing-blocks J of the winding and setting arbor. The winding and setting arbor, 55 with such set-screw loosened or released in its bearing thereon, is free to be moved lengthwise inwardly and outwardly through its bearing-blocks within a determined or certain limit. This arbor H, at its inner end has a bevel pinion-wheel, M, and near its outer end a ratchet-toothed clutching-collar, N, both attached to it, and inside of the clutching-collar is a bevel gear-wheel, O, free to turn upon it, and which is at all times in engagement with the bevel 60 gear P of the crown-wheel F. With the arbor H at the limit of its outward movement its clutching-collar N is out of engagement with a similar and corresponding-shaped clutching-collar, R, forming a part of the 65 loose bevel gear-wheel O, connected with the crown-wheel F, as described, and with the arbor at the limit of its inward movement, its clutching-collar is engaged with the clutching-collar of said bevel gear-wheel, and thus the 70 arbor is connected with the winding mechanism of the watch, so that then on being turned in the proper direction the watch can be wound.

In the winding position of the arbor above 75 described the bevel-pinion M at the inner end of the arbor is out of connection with the bevel crown-wheel S, that connects by a pinion-wheel, T, with the cannon-pinion E of the movement; but this bevel-pinion M, with the 80 arbor at the limit of its outward movement, (in which position of the arbor its clutching-collar is out of engagement with the clutching-collar of the bevel-gear O of the winding mechanism of the movement,) is in engagement 85

with the bevel crown-wheel S, connected with the cannon-pinion E, and thus the arbor is adapted for the setting of the hands.

The normal position of the winding and setting arbor is, with its clutching-collar engaged with the clutching-collar of its loose bevel-gear connected with the winding mechanism, as has been described, and the winding-arbor is held in this position by means of a bent spring, U, confined at one end, and at its free end bearing upon the circumferential conical-shaped face V of the arbor.

To disconnect the arbor from the winding movement, the arbor is pulled out, and in this movement of the arbor the spring U, bearing thereon, as has been described, then comes to a bearing upon another circumferential conical-shaped surface, W, of the arbor, and back of, or, in other words, between the conical-shaped bearing-surface V, before referred to, and the bevel-pinion M on the arbor, and through which to set the hands when in proper connection. This bearing of the spring U serves to retain the bevel-pinion M in connection with the setting mechanism, as has been described, while the arbor is being turned to set the hands; but by pushing in the arbor to disconnect it from the setting mechanism of the watch-movement, the bearing of the spring on the arbor is changed to the conical bearing-surface V, and thus the arbor is held in connection with the winding mechanism, which is its normal position, as before stated.

If the arbor in its normal position is turned in the wrong direction, as it can slide in its bearings, its clutching-collar passes freely over the clutching-collar connected with the winding mechanism, and thus no effect is produced on such mechanism; but this movement, however, of the arbor is not sufficient to put it into engagement with the setting mechanism.

It is apparent from this description that as the winding and setting arbor requires to be pulled out to connect it with the setting mechanism of the movement, there is no liability of any accidental disturbance of the position of the hands of the watch from any pressure upon or contact with the stem or pendant, detachably connected to the arbor, as described. Again, it is apparent that simply by a removal of the pendant or stem from the winding and setting arbor, the watch-movement is then free

to be removed from the case, in so far as its previous connection with the stem or pendant of the watch operated to prevent the same.

The spring U and its bearings of the arbor may be dispensed with, but it is preferable to employ them.

Having thus described my invention, I claim—

1. The combination, with a watch-movement, of a longitudinally sliding and turning arbor, H K, made in attachable and detachable parts, to permit, detached, the then removal of the movement from its case, and provided with two wheels, M O, one, M, immovable thereon, to engage the hand-setting train for setting the hands, and the other, O, loose, but otherwise confined against movement thereon, to engage the winding train for winding the watch, and a clutch, N R, in two parts, one, N, immovable, and the other, R, loose thereon, and of its said loose wheel O, substantially as described, and operating together as specified.

2. The combination, with a watch-movement, of a longitudinally sliding and turning arbor, H K, made in attachable and detachable parts, to permit, detached, the then removal of the movement from its case, and provided with two wheels, M O, one, M, immovable thereon, to engage the hand-setting train for setting the hands, and the other, O, loose but otherwise confined against movement thereon, to engage the winding train for winding the watch, and a clutch, N R, in two parts, one, N, immovable, and the other, R, loose thereon, and of its said loose wheel O, and also provided with two peripheral bearing-surfaces, V, running at opposite angles to its axis, and of a spring-arm, U, confined at one end, and at its other and free end having a bearing upon said bearing-surfaces of the arbor to prevent the accidental sliding of the arbor, substantially as described, and operating together as specified.

In testimony whereof I have hereunto set my hand in the presence of two subscribing witnesses.

CHAS. V. WOERD.
